UNITED STATES PATENT OFFICE.

GEORGE GILL, OF TAUNTON, MASSACHUSETTS, ASSIGNOR TO REED AND BARTON, OF SAME PLACE.

DESIGN FOR A TEA-SERVICE.

Specification forming part of Design No. 6,143, dated September 17, 1872.

To all whom it may concern:

Be it known that I, GEORGE GILL, of Taunton, in the county of Bristol and State of Massachusetts, have invented a Design for a Tea-Service, of which the following is a specification:

The nature of my design is fully represented in the drawing and accompanying illustrations, to which reference is made.

In the drawing the figure is a side elevation.

A is one of the articles of the set, to all of which my designs are to be applied, and it is intended to represent a tea-pot. B is the body, which is ornamented on each side with the two flowers C C, proceeding from a common point, c, and curving around in opposite directions until they nearly meet at the bottom. On each side of initial-point c is arranged a twig, D, extending downward and outside of the flowers C C, and exhibiting a plan view of the small and central end leaves D', while the longer leaves E are only exhibited in side view. From the same point c vertically projects the downward leaf F and the upward leaves G G, each presented in plan view. This constitutes my design for ornamentation of the body of each article of the set. The body B is divided into two parts, B¹ and B², with an annular fluting, B³, that connects them together. B¹ is largest at the bottom, and its circumference diminishes gradually, like a cone, until the fluted connection B³ is reached, while the part B² starting from the fluted connection enlarges, but not by equal gradations, toward the top, so as to form a concave surface and produce a flare on whose upper face rests the cover and its hinge. This constitutes my design for the form of the body. H represents the bottom, which is the section of a sphere, from which project the feet h. These are each ornamented on the upper front face with an elongated stem and sprig of leaves, h',

and terminate in a claw which grasps a flattened ball. J represents the handle, which has a downwardly-projecting piece, j, ending in a ball, j¹, a figure, j², of a lion at top, and cross-pieces j³ j⁴, which are connected by a stem, j⁴, with its leaf j⁵ at the lower end. K represents the cover, surmounted at its center by the cone k, with twig containing acorn-hulls k' k' k'. L is the spout, having the projecting enlargement l overhung by a series of pendent acorns, l', in the hull, and the slender tapering discharge l² having the equal recesses or concavities l³ l⁴ at the upper portion of the end.

Having thus described my invention, what I claim as new, and desire to secure by Letters Patent, is—

1. The design for the ornamentation of body B, consisting of the twig, flowers, and leaves, arranged as described.

2. The design for the form of body B, consisting of the parts B¹ B², constructed and connected by the fluting B³, as described.

3. The design for legs of bottom H, consisting of the claw resting upon flattened ball, and surmounted by an elongated twig and leaves, as described.

4. The design for handle J, consisting of the peculiarities j j¹ j² j³ j⁴ j⁵, as described.

5. The design for cover K, consisting of the cone k, surmounted at its center by an upright twig bearing the acorn-hulls k', as described.

6. The design for spout L, consisting of enlargement overhung by pendent acorns in the hull, and surmounted by slender discharge having equal concavities l³ l⁴ at the upper part of end, as described.

GEORGE GILL.
